UNITED STATES PATENT OFFICE.

WILLIAM D. HUNT, OF SCOTT, NEW YORK.

IMPROVEMENT IN FENCES.

Specification forming part of Letters Patent No. 67,117, dated July 23, 1867.

To all whom it may concern:

Be it known that I, WILLIAM D. HUNT, of Scott, in the county of Cortland, and in the State of New York, have invented certain new and useful Improvements in Fences; and I do hereby declare that the following is a full, clear, and exact description thereof, reference being had to the accompanying drawing, and to the letters of reference marked thereon.

In the annexed drawing, making part of this specification, A A represent the fence-posts, and B B the wires, which run from one post to another for forming the panels of fence. This is simply a wire fence composed of any desired number of wires; but for general purposes I think two will be sufficient.

C C represent a series of small spur-wheels, their spurs being sharpened, so as to prick readily. These wheels are provided with openings at their centers, through which the wire passes. The spurs fit the wire loosely, so as

to revolve easily upon it. By providing the wires with these sharp spur-wheels, animals are deterred from pushing against the fence or attempting to break over it. The spurs may be kept in their places and at suitable distances apart by means of flanges or otherwise. These spurs can be made of refuse sheet metal by dies and made very cheaply.

Having thus fully described my invention, what I claim as new, and desire to secure by Letters Patent, is—

Providing the wires of a wire fence with a series of spur-wheels, substantially as and for the purpose set forth.

In testimony that I claim the foregoing I have hereunto set my hand and seal this 3d day of June, 1867.

WM. D. HUNT. [L. S.]
